CLAIM

(21) Appl. No.: **29/442,831**

The ornamental design for a rear combination lamp for an automobile, as shown and described.

(22) Filed: **May 23, 2013**

DESCRIPTION

(30) **Foreign Application Priority Data**

Mar. 22, 2013 (KR) 30-2013-0014661

FIG. 1 is a perspective view of a rear combination lamp for an automobile according to the present invention.

(51) **LOC (10) Cl.** **26-06**

FIG. 2 is a front view of the rear combination lamp for an automobile of FIG. 1.

(52) **U.S. Cl.** **D26/28**

FIG. 3 is a rear view of the rear combination lamp for an automobile of FIG. 1.

(58) **Field of Classification Search**

FIG. 4 is a left side view of the rear combination lamp for an automobile of FIG. 1.

USPC D26/28-36; 362/459-468, 475-478,
362/485-487

FIG. 5 is a right side view of the rear combination lamp for an automobile of FIG. 1.

See application file for complete search history.

FIG. 6 is a top view of the rear combination lamp for an automobile of FIG. 1; and,

(56) **References Cited**

FIG. 7 is a bottom view of the rear combination lamp for an automobile of FIG. 1.
